DISPENSING CABINET FOR ROLLED PAPER STRIPS

Frank P. Vaughan, Albert G. Krueger, and Norman J. Slye, Green Bay, Wis., assignors to Bay West Paper Company, Green Bay, Wis., a corporation of Wisconsin

Application June 10, 1938, Serial No. 212,930

8 Claims. (Cl. 164—84.5)

This invention relates to improvements in dispensing cabinets for rolled paper strips.

In Patent 2,139,339 issued upon a co-pending application, Serial No. 76,442, filed April 25, 1936, a dispenser for paper articles is disclosed which requires successive manual operations to deliver from an interior roll of paper a single measured length or sheet to be severed from the strip upon delivery. In that structure a manually operable control slide was employed to unlock crank operated mechanism. In so doing, the slide was itself locked in inoperative position subject to release by the paper severing operation.

In the present application, the object is to provide means, temporarily concealed by the discharging paper, for releasing the control slide independently of and subsequent to exposure of said concealed releasing means by the severance of the previously delivered sheet.

More specifically, it is the object to provide such a cabinet with a sliding unlocking means, a revoluble paper delivering means, and an oscillatory member for restoring the unlocking means to operative position, whereby successive manual operations are required after delivery of each measured sheet of paper before another sheet can be delivered.

In the drawing:

Figure 1 is a vertical sectional view drawn to line 1—1 of Figure 2.

Figure 2 is a sectional view drawn to line 2—2 of Figure 1.

Figure 3 is an elevation of the control box, with the inner wall removed to show the feed controlling mechanism, the view being taken on line 3—3 of Fig. 2.

Like parts are identified by the same reference characters throughout the several views.

The cabinet 10, paper supply roll 11, feed roll 12, pinch roll 13 and severing blade 14 conform to standard practice in the construction of paper feeding cabinets in which paper is stored in the form of a continuously rolled strip. The paper strip *a* has one end passed between the feed roll 12 and the pinch roll 13, and extends downwardly through the slot 15 in the bottom of the cabinet across the severing margin 16 of the blade 14. The pinch roll is supported by bell cranks 17 pivotally supported from the bottom of the cabinet and urged in the direction of the feed roll by a spring 18 coiled about the pivot shaft. The paper is withdrawn from the roll and fed through the slot by rotating the feed roll 12, this feed roll being mounted on a shaft 19 which

extends through one end wall of the casing and is provided with a manually operable crank 20.

As shown in said former application, the end of shaft 19 opposite that provided with crank 20 extends into a control box 25 attached to the opposite end wall of the cabinet. In this control box, Figure 3, shaft 19 is provided with a single toothed disk 27. Normally the single tooth 28 on the disk 27 is loosely engaged between the pawl 29 and the cam face 30 of the cam gear 31 carried by a trunnion 32 projecting from one side of the control box. The cam gear is held against one side of the box 25 by the star-shaped spring 33.

To adjust the cam gear to disk releasing position a control slide 35 is employed. This is provided with a vertically sliding finger 36 adapted to engage the cam shoulder 37 when the slide 35 is moved to the right from the normal position in which it is shown in Figure 3. The slide 20 is actuated manually by means of a pin or handle 39, which projects through a slot 40 in the end wall of the cabinet. The inner end of this pin or handle is loosely received in a slot 41 formed in the slide 35, and when the slide is in its normal position the pin 39 is at the inner or right hand end of the slot, whereby pressure upon the pin tends to push it to the right actuates the slide 35.

Thereupon finger 36 operates the cam gear 30 out of the path of the disk tooth 28 and simultaneously releases a vertically movable trip bar 42 to withdraw its shoulder 43 from engagement with a catch plate 44. The trip bar 42 is then lifted by a tension spring 45 until its upper end 35 enters a notch 46 in the slide 35 to hold the slide in its right hand position, the slide being urged to the left toward normal position by its tension spring 48.

The handle 20 may then be rotated in a clockwise direction to cause the feed roll 12 to progressively withdraw the paper strip from the roll 11 and feed it through the slot 15 with the aid of the pinch roll 13. During the first revolution of the feed roll, the associated tooth 28 engages the cam shoulder 49 and partially restores the cam to its full line position.

During the second revolution of the feed roll the tooth 28 engages the cam shoulder 50 and restores the cam gear to its full line position, 50 as shown in Figure 3. During these return movements of the cam gear its top face raises the latch finger 36 from its dotted line position to a position in which it rests directly upon the flat top face 52 of the cam gear, and as the feed 55

roll completes its second revolution its associated tooth **28** again engages the cam face **30** as in Figure 3.

A strip or section of paper will then have been withdrawn from the cabinet and will be of a length equal to twice the circumference of the feed roll. This strip can thereupon be severed across the edge **16** of the blade **14**, but the feed roll will be locked against further revolution. The controlling slide **35** will still be held in inoperative position by the trip latch **42**, and the latter must be released to permit any further paper withdrawing operation.

To provide for releasing the trip latch, its lower end is provided with a foot piece **55**, engaged by an arm **56**, Figures 2 and 3, carried by a rock shaft **57** having a short arm **58** in the path of the short arm **59** of a lever, which is pivoted at **60** to the floor of the cabinet and has an operating arm **61** extending through a slot in the floor to a point substantially underneath the paper exit slot **15**. The lever **61** is preferably a wide plate, having a lower end portion over which the delivered paper may be fed, and after a delivered section has been severed this wide flat arm of the lever will be exposed.

Until the delivered portion of the web has been severed on the tear-off knife, the manually operable arm **61** of the releasing lever is not merely concealed from view but is rendered relatively inaccessible by the portion of the web depending below the cabinet from the dispensing slot **15**. Thus, while the severance of the projecting portion of the web on the tear-off knife **14** is not absolutely prerequisite to the release of the detent to permit another operation of the feed roll, the tearing of the projecting sheet portion of the web is nevertheless a usual preliminary to the actuation of the release mechanism.

If the arm **61** is pulled forwardly by the operator its motion will be transmitted through its short arm **59**, arm **58** of rock shaft **57**, and its longer arm **56** to depress the trip latch **42** and release the slide **35**. Thereupon the slide **35** will be restored to its normal position by its spring **48**, and its finger **36** will drop by gravity from the top **52** of the cam gear to its full line position as shown in Figure 3. All of the parts will then have been restored to normal position ready for the release of another sheet section by pressure upon the handle or pin **39** to again retract the controlling slide **35**.

The upward urge of the trip latch **42** may be varied by varying the tension of its spring **45**. To accomplish this, a spring tensioning lever **65** is employed. The spring **45** is attached to the inner arm of this lever. The other arm of this lever extends through a slot in the control box and is provided with a detent, as indicated at **66**, to engage teeth **67** formed in one wall of the slot. Downward movement of the protruding end of the lever, including lateral movement to release it from the engaged tooth **67**, will increase the tension of the spring **45**, whereas a reverse movement will decrease its tension.

From the foregoing description it will be understood that the improved cabinet has its outfeeding slot flanked on one side by a severing blade and on the other side by the exposed arm of a setting lever permitting operation of interior feed control mechanism. After adjusting the same lever to permit operation of the feed control mechanism, slide **35** returns to normal position, pending further manual adjustment of an exposed operating piece **39**.

Also, that when such adjustment is made, an outfeeding mechanism can be operated to a limited extent to feed through the slot a portion of the paper strip of predetermined length, whereupon the above described cycle of operations must be repeated before the feeding of another measured strip can be accomplished.

The feature of organization, which locates the latch releasing lever behind the discharging sheet or section of the strip, is important. While the latch releasing arm **61** is normally in plain view, it is concealed as soon as the discharging paper moves down in front of it, and the operator will not be tempted to reach around the paper strip and pull the lever forwardly simply for the purpose of enabling him to continue the delivery by again pushing on the arm or pin **39** as soon as the outfeeding operation is stopped by the cam gear.

Therefore, each sheet will ordinarily be torn away when the feeding stops, and if another sheet is desired, the lever **61** will then be pulled forwardly to renew the cycle of operations.

We claim:

1. The combination of a dispensing cabinet for rolled paper strips, said cabinet having an outfeeding slot and a manually movable releasing member behind the path of paper delivered through the slot, normally locked feeding mechanism within the cabinet adapted, when unlocked, to be manually actuated to deliver a measured portion of the strip through said slot, a one-way operable unlocking device, a trip for preventing return of the unlocking device to normal position, and means for transmitting movement of the releasing lever to retract the trip and allow the unlocking device to return to normal position for a succeeding unlocking movement.

2. In a slotted cabinet provided with means for supporting a rolled paper strip and outfeeding mechanism for delivery of the strip in successive sheets through the slot in the cabinet wall, the combination with such outfeeding means of locking mechanism normally preventing its operation, an unlocking slide cooperative with the locking mechanism to limit the extent of each outfeeding operation, an automatically actuated latch for preventing a return of the unlocking slide for a succeeding unlocking operation, and oscillatory means operable from the exterior of the cabinet to release said latch and permit such return.

3. A dispensing cabinet for rolled paper strips, having an outfeeding slot and a normally locked interior outfeeding roller, a control slide within the cabinet and associated means for unlocking the roller for limited feeding movement, means for manually operating the control slide in one direction from the exterior, an interior trip for automatically preventing retraction of the control slide, and a manually operable lever for releasing the trip disposed behind the path of paper issuing from the slot in a position to be substantially concealed thereby, said control slide being provided with resilient means for restoring it to its manually operable position when released by the trip.

4. The combination with mechanism for dispensing a web from a roll, said mechanism comprising feeding means and measuring mechanism for limiting each operation of said feeding means to the delivery of a predetermined length of said web, of a detent requiring release prerequisite to each operation of said feeding means, a tear-off

knife disposed forwardly of the path of web delivery and a manually operable member in operative connection with said detent for the release thereof, said member being disposed behind the path of delivery of said web by said feeding means, whereby to be inoperable by said web during severance of a delivered length thereof and positioned to be materially obscured from view by the delivered portion of the web prior to its severance.

5. The combination with means for supporting a roll and feeding a web therefrom, of measuring mechanism in operative connection with said means comprising a stop actuated by said means and engageable with said means after a predetermined actuation to restrict said means against delivery of more than a given portion of web from said roll in a single operation, and mechanism for controlling the resetting of said stop to 20 permit a further operation of said means, said mechanism comprising a manually operable trip disposed behind the path of advance of a web delivered by said means and operatively connected to move forwardly in its resetting of said 25 stop, whereby said trip will be inoperable by pressure of said web and materially concealed by said web pending the severance of the concealing portion of said web from the remainder thereof.

6. The combination with web feeding and 30 measuring mechanism provided with a detent for limiting the operation of said mechanism for the control of the length of web dispensed in each operation thereof, of a trip requiring resetting prerequisite to the release of said detent and disposed at the rear of the path of material delivered from said mechanism and operatively connected to move forwardly in its resetting of said 35 stop, whereby to be inoperable by pressure of said web and materially concealed by the delivered web pending the removal thereof.

7. In a device of the character described, the combination with means providing a dispensing slot, of a feeding and measuring mechanism above said slot for the delivery of a web therethrough, said mechanism comprising a releasable detent 5 for restricting the operation of said mechanism to the delivery of a predetermined length of web, and a trip operatively connected with said detent for the release thereof and comprising a lever pivoted to said first means behind said slot and 10 having a manually operable portion movable toward the path of web delivery through said slot in the course of its trip releasing movement, and said portion being positioned to be substantially obscured by the delivered web pending the 15 removal thereof.

8. The combination with a dispensing cabinet for a paper web, said cabinet having a downwardly opening transversely extending outfeeding slot and provided at one side of said slot with 20 a sheet severing blade and at the other side with a manually movable releasing lever pivoted to said cabinet for forward movement from a normally retracted position toward the path of a web dispensed through said slot and positioned 25 to be substantially concealed by a web portion delivered from the slot, of interior feeding mechanism adapted to deliver a measured portion of web through said slot, a latch requiring retraction prerequisite to the operation of the feeding 30 mechanism, and latch retracting connections between said manually operable releasing lever and the latch and subject to actuation in a latch releasing direction upon a forward movement of the lever upon its fulcrum respecting said cabinet 35 after the web is cut off by said sheet severing blade.
